KNITTING MACHINE

Kenneth Howie and Charles C. Krieble, Norristown, Pa., assignors to Wildman Mfg. Co., Norristown, Pa., a corporation of Pennsylvania

Application October 18, 1941, Serial No. 415,654

44 Claims. (Cl. 66—96)

This invention relates to knitting machines of the full fashioned type, and more particularly to mechanism therefor for turning the welt of a lady's full fashioned hose knit on such a machine.

With the mechanism of this invention, the yarn of the initial course of the fabric is automatically caught upon points, and these points subsequently automatically deliver the loops of that initial course to the needles in order to close the welt.

Furthermore, after the loops of the initial course of the fabric have been delivered to the needles, the points are automatically removed to an inactive position so that knitting of the remainder of the fabric will proceed without interruption.

As a further feature of the invention, a welt rod is automatically dropped into place sometime before the welt is closed, and since the fabric take-up belts are connected to this welt rod, the operation of the machine is not interrupted.

As a further feature of the invention, the loops of another course of the fabric become placed upon the points during the welt turning operation, and they also are delivered to the needles so that a strong junction of the fabric results.

The invention also includes a welt point of a novel construction for carrying out the welt turning operation.

Other features of the present invention will hereinafter appear.

Because of the features of the invention resulting in a completely automatic turning of the welt, manual intervention is not necessary after the machine has been set in operation to lay the initial yarn.

The mechanism of the invention is here shown applied to a single-head, full fashioned knitting machine of the type disclosed in Howie Patent No. 1,982,991, granted on December 4, 1934, and reference may be had to that patent for details of the knitting machine not illustrated in the present drawings.

In the drawings

Figures 1 to 4, inclusive, show successive steps in the operation of the machine by which the initial lay of yarn upon the needles is caught upon the welt points.

Fig. 5 shows the relation of the parts after a portion of the welt has been knit, and just before the welt rod is folded in the fabric.

Figs. 5a and 5b are enlarged views showing the manner in which another course of the fabric is caught upon the welt points as an incident to folding in of the welt rod.

Fig. 6 shows the relation of the parts after the welt rod has been folded into the fabric.

Fig. 6a shows the relation of the parts at the completion of the knitting of the welt fabric.

Fig. 6b shows the relation of the parts after the first step in the return of the welt points to the needles to close the welt.

Figs. 7 to 12, inclusive, show successive steps in the operation of the machine by which the loops upon the points are transferred to the needles in order to close the welt.

Fig. 13 is an enlarged front view of the lower end of the welt point employed in carrying out the invention.

15 Fig. 13a is a section on an enlarged scale on line 13a—13a of Fig. 13.

Fig. 14 is a side view of Fig. 13.

Fig. 15 is a perspective view of the upper portion of the knit fabric, showing the closed welt.

20 Fig. 16 is a section on the line 16—16 of Fig. 15, on an enlarged scale.

Fig. 17 is a side elevation of the upper portion of a knitting machine embodying the structure of the invention, the view being taken from the 25 righthand side of Fig. 18, and the side frame and other parts of the knitting machine being removed to better show the welt turning mechanism.

Fig. 18 is a front elevation of Fig. 17, the forward ends of the frame and the fabric take-up reel being omitted.

Fig. 19 is a plan view of Fig. 17.

Fig. 20 is a section on the line 20—20 of Fig. 18, on an enlarged scale.

35 Fig. 21 is a section on the line 21—21 of Fig. 18, on an enlarged scale.

Fig. 22 is a section on the line 22—22 of Fig. 18, on an enlarged scale.

40 Fig. 23 is an elevation on an enlarged scale of the left-hand side of Fig. 18.

Fig. 24 shows a portion of Fig. 23, the parts having been moved to a different position.

Fig. 25 is a view on the line 25—25 of Fig. 24.

45 Fig. 26 is a section on the line 26—26 of Fig. 18, on an enlarged scale.

Fig. 27 is a section on the line 27—27 of Fig. 24.

Fig. 28 is an enlarged view, partly in section, showing the details of the stop means for limiting 50 axial movement of shaft 128.

Fig. 29 is an enlarged view, partly in section, showing the details at the lower end of the lever for shogging shaft 128.

Fig. 30 is a section on the line 30—30 of Fig. 23, 55 on an enlarged scale.

Fig. 31 is a section on the line 31—31 of Fig. 30.
Fig. 32 is a plan view of Fig. 30.

Fig. 33 is a section on the line 33—33 of Fig. 19, on an enlarged scale.

Fig. 34 is a section on the line 34—34 of Fig. 19, on an enlarged scale.

Fig. 35 is a view taken from the line 35—35 of Fig. 33.

Fig. 36 is a fragmentary plan view showing a portion of the welt rod and its connection to a fabric take-up belt, in its relation after the welt has been turned.

Fig. 37 is a perspective view of the welt rod.

Fig. 38 is an enlarged view of the cam which causes movement of the welt bar toward and away from the needles, its direction of rotation being indicated by an arrow.

Fig. 39 is an enlarged view of the cam which causes up and down movement of the welt bar, its direction of rotation being indicated by an arrow.

Fig. 40 is an enlarged view of the drive ratchet on the auxiliary cam shaft.

Fig. 41 is a section on the line 41—41 of Fig. 19, on an enlarged scale.

Fig. 42 is a front elevation of an end portion of the picot bar, showing the welt rod guard attached thereto.

Fig. 43 is an end elevation of Fig. 42, showing the relation of the welt rod to its guard.

Fig. 44 is a perspective view of the guard for the welt rod.

Referring first to Figs. 13, 13a, and 14 in particular, the welt point 50 employed to carry out the invention is formed at its lower end with a curved portion 52, the concaved side of which faces toward the beard of the needle when the point is on the beard side of the needle. Into this concaved side is formed a notch which will provide a shoulder 51 to retain a yarn upon the point. The extreme lower end 54 of the point is reduced as appears in Fig. 14 so that it will more readily enter a loop of the fabric, as will later appear. Upwardly from the shoulder 51, and on the same side of the point, is an eye 53 to receive the beard of the knitting needle 55.

The shoulder 51 preferably is of less width than the stem therebehind, so that the stem serves as a shield to the shoulder. This shielding effect of the stem with respect to the narrower shoulder will serve to insure transfer of the loops from the points of the needles without the yarn catching upon the shoulder. To obtain this shielding relation, the portion of the point 50 below the notch providing the shoulder 51 may be thinned or flattened, as appears in Figs. 13 and 13a.

The curvature of the lower end of the point has several advantages. It removes the shoulder 51 of the point away from the needle beard when the beard is in the eye 53 of the point, and at the same time enables the lower end 54 of the point to enter an eye 60 in the needle below the beard as shown in Fig. 10. This curvature of the lower end of the point also will cause it to retain a yarn which may not have become caught upon the shoulder 51, and additionally serves to facilitate movement of the lower end of the point between the needles and sinkers. The thinning or flattening of the lower portion of the point 50 further facilitates this movement of the lower end of the point between the needles and sinkers.

The position of the parts at the start of knitting a fabric is shown in Figs. 17, 18, and 19. This is the position which the parts assume after the previously knit fabric has been dropped from

the needles. The succeeding steps for accomplishing turning of the welt of a new fabric are shown in Figs. 1 to 12, inclusive. As shown in Fig. 17, the points 50 are initially located on the beardless side of the needles 55, and at quite a distance from them. There is a point for every needle, and the points are in line with the needles and not in line with the spaces between the needles. This is the position of the points during the knitting of the part of the previous fabric after its welt has been fully turned.

In moving to the position shown in Fig. 1 to start a new fabric, the points 50 have been moved toward the needles from the position of Fig. 17, and have also been elevated slightly. At the end of this time, the needles are at their elevated position at which the yarn is laid upon them, and the yarn carrier 57 is advancing lengthwise of the needle row to lay the first yarn. As also shown in Fig. 1, the sinkers 56 are being advanced in order to sink the yarn about alternate needles.

To reach the position of Fig. 2, the dividers have been first advanced and the needles have then been moved downwardly so that the tops of the needles are at the throats of the sinkers and dividers. Also the needles have been moved rearwardly so as to bring the beards of the needles against the presser bar 58. In the position of Fig. 2, the points 50 have been moved to the beard or operating side of the needles. To result in the relationship shown in Fig. 2, it is not necessary that the points 50 be raised in moving from the position of Fig. 1 in order to position them on the beard side of the needles, because the needles have been lowered to such a position that the mere rearward movement of the points 50 will bring them to the beard sides of the needles without contact with the needles.

In the position of Fig. 3, the needles have been moved away from the presser bar 58 in order to drop the yarn off of the nose of the sinkers and dividers. This dropping off of the yarn is assisted by a simultaneous rearward movement of the sinkers and dividers. During this movement of the needles, and sinkers and dividers, the points 50 have been lowered so that their shoulders 51 are below the yarn. The lower ends of the points 50 are now between the knockover bits 59.

In Fig. 4, the needles have been moved still further downwardly so that the tops of them are below the upper surface of the knockover bits 59. This movement brings the yarn downwardly upon the tops of the knockover bits. At this time, the points 50 are shogged in a direction lengthwise of the needle row a half needle space so that they will be out of alignment with the needles and will be in line with the spaces between the needles. The needles are then moved rearwardly toward the throat of the knockover bits 59, and because of the disalignment of the points and needles, the needles are caused to pass by the points without collision occurring between them. In Fig. 4, the points are shown in the position of this movement in which they are alongside of the needles. The thinning out of the lower ends of the points as shown in Fig. 13 is important in order to permit this passage of the needles past the points even though they are located between the knockover bits at this time.

After the points are on the beardless side of the needle row, they are shogged back into alignment with the needles. As a result of the movement of the needles between the points, the

sinker and divider loops are caught upon the shoulders 51 of the points 50. The points 50 serve to maintain the initial yarn kinked around the needles, so that the next yarn which is laid down upon the needles will be knit onto this initial kinked yarn and regular knitting loops will be formed. Regular knitting may therefore proceed.

In Fig. 5, a portion of the welt is shown as having been knit. During this knitting of the welt, the points 50 are moved away from the needles under the influence of the usual fabric take-up means in order to take up the fabric as it is knit. During the movement of the points 50 away from the needles while the welt is being knitted, the points 50 remain at the same level.

In Fig. 6, the knit fabric is the same as that of Fig. 5, but the welt rod 170 has been dropped in place. Also, the points 50 have been moved slightly toward the needles and have been elevated in order to fold the fabric over the welt rod. Tension of the fabric take-up on the rod urges the rod away from the needles.

As a result of this folding of the fabric over the welt rod, the loops of two courses are now upon the points, and this constitutes an important feature of the invention. The manner in which the loops of two courses are positioned upon each point is shown in the enlarged detail views of Figs. 5a and 5b.

In order to readily accomplish this location of the loops in two courses upon the welt points 50, it is desirable that the first course 62 be knit as a loose stitch, that the second course 63 be knit as a tight stitch, and that the third course 64 which is knit be a loose stitch. The remainder of the welt fabric may be of a uniform tight stitch. As shown in Fig. 5a, at the start of the folding of the fabric over the welt rod, the yarn will be brought against the lower rear portion of the points. In this position shown in Fig. 5a, the loose course 64 is close to the lowermost end 54 of the point 50. Further folding over of the fabric will cause the loose course 64 to be brought under the lowermost tip 54 of the welt point 50, and will then cause the tip 54 to enter the loose course 64 as shown in Fig. 5b. When the loose course 64 is then urged upwardly so as to lie close to the loose course 62 already upon the welt point, these loops of two courses of the fabric will be positioned one above the other upon the welt point, so that they may be transferred in unison to the knitting needle.

In Fig. 6a, the complete welt fabric has been knit, the points having remained in the same position which they occupy in Fig. 6, and the welt rod having moved away from the needles to take up the fabric. As a feature of the invention, additional tension is applied to the take-up means during the knitting of the fabric when the welt rod is folded in the fabric, in order to compensate for the frictional drag of the fabric over the rod and for the tension in the fabric between the welt rod and the points. From the position of Fig. 6a, the points are moved toward the needles to close the welt, the additional take-up tension being released at this time.

In Fig. 7, the needles are moving through their regular needle narrowing motion, and have moved downwardly so that their upper ends are approximately at the level of the sinker throat. The welt points 50 have been moved to and over the tops of the needles so that they now occupy a position to the rear of the needles. In order to reach the position shown in Fig. 7, it is neces-

sary that the points be elevated from the level shown in Fig. 6.

In Fig. 8, the needles have moved downwardly from the position of Fig. 7, and also have moved towards the presser bar 58. The welt points 50 have moved downwardly on the beard side of the needle, and have carried the fabric which is upon the points downwardly below the sinkers. This fabric now rests upon the tops of the knockover bits 59.

In Fig. 9, the welt points 50 have moved downwardly so that their eyes 53 are opposite the beards of the needles. This downward movement of the welt points has caused the fabric to be pushed upwardly along the welt points by the knockover bits 59 so as to lie above the eye 53 of the points. In Fig. 9, the sinkers have been moved forwardly from their position in Fig. 8, so that they overlie the needles and also overlie the fabric.

In Fig. 10, the needles have progressed through their narrowing motion and have moved in a direction toward the presser bar 58. This movement has brought the beard of each needle 55 into the eye 53 of a welt point 50. Also, the lowermost tip 54 of each welt point 50 has entered the eye 60 in each needle below the beard.

In Fig. 11, the welt points and the needles have been moved upwardly in unison with each other. The overlying sinkers 56 serve to prevent upward movement of the fabric with the points and needles, so that the yarn is stripped downwardly off of the points. The upward movement of the needles causes them to enter the loops 62 and 64 upon the points 50, and in this manner transfer of the yarn from the points to the needles is accomplished.

In Fig. 12, the needles have been moved so far upwardly that the fabric is now below the beard of the needles. The points have been moved upwardly to a position above the tops of the needles, and from this position the points may move away from the presser edge to the position shown in Fig. 17, which the points normally occupy. As has been stated, the points remain in this position shown in Fig. 17 during the subsequent knitting of the fabric.

From the position shown in Fig. 12, the needles will be moved upwardly to their position shown in Fig. 1, so that they may receive a new yarn which is to be laid down and which will be drawn through the loose loops 62 and 64, and also through the loops shown upon the needles in Fig. 6a. In this manner, the welt is completely closed, as shown in Fig. 16, and the loops 62 and 64 will be joined to the fabric. Thereafter the needles will be caused to successively pass through their regular knitting motion, so that the portion of the fabric following the welt will be knit, and the fabric shown in Fig. 15 will result.

To support the welt points 50, they are carried in a welt bar 65 which includes a front clamping plate 66. The welt bar 65 is permanently attached at its ends to side arms 67 and 68. The other ends of the side arms 67 and 68 from their points of attachment to the welt bar 65 are pivotally connected to upright arms 69 and 70, respectively. The side arm 67 is pivotally connected to the upright arm 69 by means of a bolt 71 which passes freely through a bearing end portion of the arm 69 and is threaded in the arm 67. A like bolt 72 serves to pivotally connect together the side arm 68 and the upright arm 70.

The lower ends of the upright arms 69 and 70 are pinned to a rock shaft 74. Rock shaft 74 is

rotatably mounted in bearings in the lower ends of hangers 75 and 76. The upper ends of the hangers 75 and 76 are permanently secured to a trough-shaped member 77. The opposite ends of this trough-shaped member 77 are rigidly secured to the side frames 78 and 79 of the machine framework, so that the trough-shaped member 77 is a fixed part of the machine.

The central portions of the arms 69 and 70 are bent outwardly away from the machine, so that they lie beyond the ends of the trough-shaped member 77, and also outside of the side frames 78 and 79. This formation of the arms 69 and 70 permits a greater arc of movement of the arms, since the trough-shaped member 77 and side frames 78 and 79 do not limit their movement.

In order to adjust the upright arms 69 and 70 with respect to rock shaft 74, their lower ends are split, as best shown in Fig. 20, to provide a thin portion 81 and a rigid portion 82. The thin portion 81 is integral with the arm 70, and because it is thin and slightly flexible, the angular position of the arm 70 about the shaft 74 may be changed. The rigid portion 82 should be of such strength that its relationship with respect to the rock shaft 74 will remain relatively fixed. A sleeve 83 is threaded into the upper end of the rigid portion 82 and bears against the arm 70 so as to force the arm 70 away from the rigid portion 82. Passing through the sleeve 83 is a bolt 84 which is threaded into the arm 70. Bolt 84 is not threaded into sleeve 83, but the head of bolt 84 bears against the outer face of sleeve 83 so that by screwing inwardly this bolt 84, the arm 70 will be drawn toward the rigid portion 82. By adjusting the sleeve 83 and the bolt 84, therefore, the upright arm 70 may be adjusted with respect to the rigid portion 82. In this manner, arms 69 and 70 may be fixed with respect to shaft 74.

In order to turn the rock shaft 74, it has affixed thereto a driving arm 85 which carries a roller 86 at its free end, and this roller bears upon a cam 87 secured to a cam shaft 88. Rotation of the cam shaft 88 will cause the arms 69 and 70 to move back and forth in unison with each other. The conformation of the periphery of cam 87 will be explained in connection with the general operation of the machine.

To swing the arm 85 toward the cam 87 so that the roller 86 will follow the cam 87, a torsion spring 89 (Fig. 18) is located upon the shaft 74. One end of this torsion spring 89 is embedded in a recess in the adjacent face of the hanger 76, and the other end of the spring is embedded in a recess in a collar 90 which may be affixed to the rock shaft 74. By rotating the collar 90 about the shaft 74, and fixing it in position, the force exerted by the spring 89 to cause the roller 86 to bear against the cam 87 may be increased or decreased. The spring 89 need not be strong, since it is not relied upon to apply tension to take up the welt as it is knit.

The cam shaft 88 is rotatably mounted in bearings in the hangers 75 and 76. In order to rotate the cam shaft 88, it has pinned thereto a ratchet wheel 91 having five notches in the periphery thereof. The notches 92a, 92b, 92c, and 92d are a quarter turn apart, and notch 92d is midway between notches 92c and 92e (see Figs. 21, 22, and 40). Rotatably mounted upon the shaft 88, and at one side of the ratchet wheel 91, is a pawl carrier 93. This pawl carrier 93 is retained against the ratchet wheel 91 by a collar 94 se-

cured to the shaft 88. To the outer end of the pawl carrier 93 is pivotally attached a pawl 95, and a spring 96 urges this pawl toward the periphery of the ratchet wheel 91 so that it will engage the notches therein.

In order to operate the pawl carrier 93 and thereby rotate the ratchet wheel 91, a link 97 is pivotally connected to the pawl carrier and is also pivotally connected to one arm of a lever 98 (Fig. 17). The lever 98 is pivotally mounted upon a shaft 99. This shaft 99 occupies the position of the shaft appearing in Fig. 6 of the aforementioned Howie Patent No. 1,982,991, to which the cam 70 is affixed. In order to accommodate the lever 98, the shaft 99 must be elongated beyond its length shown in Patent No. 1,982,991. The other arm of the lever 98 has rotatably attached thereto a roller 101 which bears upon a cam 100 secured to the main cam shaft a of the knitting machine. This main cam shaft a is the same as that appearing at a in the knitting machine illustrated in Howie Patent No. 1,982,991.

A spring 102 causes roller 101 to follow cam 100, the lower end of this spring being connected to the machine frame work. From Figs. 17 and 21 it will be apparent that the thrust of pawl 95 which actually serves to rotate shaft 88 is due to the pull exerted by spring 102 and is not due to a force exerted by the cam 100. The cam 100 merely lifts roller 101 so that the spring 102 can become active to give the pawl 95 its driving thrust.

During the operation of the machine, the pawl carrier 93 oscillates back and forth repeatedly, and pawl 95 would therefore tend to constantly rotate the ratchet wheel 91 if means were not provided to interrupt its operation. To determine when the pawl 95 shall engage a notch in wheel 91, a shield 104 is pivotally mounted upon a bolt 105, which is threaded into a lug 106 projecting from the side of the hanger 75. This shield 104 lies close to the side of the ratchet wheel 91, and its outer surface is curved to conform generally to the circular periphery of the ratchet wheel 91. The pawl 95 is wide enough at the notch engaging portion thereof to bear upon the shield 104, and the pawl 95 will therefore ride back and forth upon the shield and be prevented from engaging into any notches in wheel 91 when the shield is out.

To move the shield inwardly toward the shaft 88 and thereby permit the pawl 95 to engage a notch in wheel 91, an arm 107 of the shield is pivotally attached to a link 108. The lower end of link 108 is pivotally connected to a lever 109 (Fig. 17) which at one end is pivoted to a fixed part of the machine. The free end of lever 109 bears upon the pattern drum A which is shown in Howie Patent No. 1,982,991. Buttons 110 and 111 affixed to the pattern drum A will lift the lever 109 and thereby serve to swing the shield 104 inwardly away from the periphery of the ratchet wheel 91 to thereby permit the pawl 95 to enter one of the notches therein. Thus, although the pawl 95 is constantly oscillated during the operation of the machine, it will act upon the ratchet wheel 91 to rotate it only at the times that the shield 104 is acted upon by a button 110 or 111 upon the pattern drum A.

From Fig. 17 it will be observed that buttons 110 are low, whereas button 111 is high. A high button necessarily swings the shield 104 further toward the shaft 88 than does a low button. Also, from Fig. 40 it will be observed that notches 92a, 92c, and 92d are located further radially outward-

ly from the center of ratchet wheel 91 than are notches 92b and 92e. A low button 110 will move the shield 104 inwardly only far enough to permit the pawl 95 to engage one of the outer notches 92a, 92c, or 92d, it being necessary for a high button 111 to act in order to swing the shield inwardly sufficiently far to permit the pawl 95 to engage one of the inner notches 92b or 92e.

This relation between the high and low buttons on pattern drum A, and the inner and outer notches in ratchet wheel 91, make it unnecessary to immediately rotate the pattern drum to remove a button from beneath the lever 109 after that button has served to initiate rotation of shaft 88. For example, it may be assumed that ratchet wheel 91 is in position for the pawl 95 to engage in notch 92a, but this engagement is prevented because no button on the drum A is beneath lever 109. To cause the pawl to engage the notch 92a, a low button 110 is brought beneath lever 109, and the ratchet wheel 91 is thereby turned a quarter turn. The ratchet wheel is now in position for its notch 92b to be engaged by the pawl 95, but the shield 104 prevents such engagement as it is not inwardly sufficiently far to uncover the notch 92b.

The shaft 88, therefore, will not be turned even though the button 110 remains under the lever 109 and the drum A is not turned. When it is desired that the pawl 95 engage the notch 92b, a high button 111 is brought into action to cause the shield 104 to move inwardly sufficiently far to uncover the notch. Thus, due to the relation between the high and low pattern buttons, and the inner and outer ratchet wheel notches, repeated operation of the shaft 88 is prevented, even though a low button remains under lever 109.

It is desirable that the cam shaft 88 be positively retained in the position to which it is moved after each driving action of the pawl 95, and for this purpose, an index wheel 112 (Fig. 22) is pinned to the cam shaft 88. A detent 113 is slidably positioned in lugs 114, 115 projecting from the hanger 75, and a spring 116 urges the detent 113 against the periphery of the index wheel 112. The periphery of the index wheel 112 is formed with notches into which the detent 113 will engage to retain the cam shaft against accidental rotation.

To guide the side arms 67 and 68 in their forward or backward movement under the action of cam 87, guide arms 122, 123 are provided. At their upper ends, the arms 122, 123 are formed with elongated projecting portions 124, 125, respectively, and with overhanging portions 126, 127, respectively. A pin 118 projecting from the side of arm 67 rides upon the upwardly facing surface of the extension 124, and may enter into the recess between this surface and the overhanging portion 126 (Figs. 24, 25). In like manner, a pin 119 of arm 68 (Fig. 17) will ride upon the upwardly facing surface of the forward extension 125 of arm 123, and may recede so as to enter between this surface and the overhanging portion 127. Flanges 120 and 121 at the ends of pins 118 and 119, respectively (Fig. 25), bear against inner opposing faces of guide arms 122 and 123 to fix the endwise position of the welt bar 65.

The guide arms 122 and 123 are carried by a shaft 128 which is rotatably mounted in bearings in the hangers 75, 76.

The arm 123 is loose upon the shaft 128, and in order to connect it to the shaft 128 so that

it will be moved by the shaft, a connecting arm 130 (Figs. 18, 26) is pinned to the shaft 128 adjacent to the arm 123. A bolt 129 passes through a lug portion 131 of the arm 123, and is bolted into the connecting arm 130 in order to firmly hold them together. The opening in the lug portion 131 of the arm 123 through which the bolt passes is preferably of arcuate shape about the axis of shaft 128 in order to permit a limited angular adjustment between the arm 123 and the connecting arm 130.

To facilitate adjustment of the angular relationship between the guide arm 123 and the connecting arm 130, a bolt 133 is threaded into an offset portion 134 of the connecting arm 130, and bears upon the lug portion 131 of the arm 123. A lock nut 132 upon bolt 133 holds it against rotation. By loosening lock nut 132 and bolt 129, and then screwing the bolt 133 inwardly or outwardly, the arm 123 can readily be brought to its desired point of adjustment.

The arm 122 has an opening therethrough (Fig. 23) to receive shaft 128, but the arm 122 is not fixed directly to the shaft 128, but instead is attached by means of a bolt 136 to an actuating arm 137 which is pinned at 135 (Fig. 18) to the shaft 128. The passage of the shaft 128 through the arm 122 and the clamping action of the bolt 136 serve to positively fix the angular position 30 of the arm 122 with respect to the shaft 128.

The actuating arm 137 extends downwardly to a position for its lower end to be borne upon by a lifting cam 138 affixed to the cam shaft 88. In order to provide an adjustment between the cam 138 and the lower end of the arm 137, a flexible shoe 139 is affixed by means of a screw 140 to the arm 137. By means of an adjusting screw 141, the lower end of the shoe 139 may be positioned closer to, or away from, the lower end of 40 arm 137, and thus provide a limited amount of adjustment. The shoe 139 is formed at its lowermost end with an offset portion providing a nose 142 (Fig. 27) which bears directly upon the periphery of cam 138. Spring 143 draws arm 137 45 toward the cam 138.

In order to permit the shogging movement of the welt bar 65 which has been described, the shaft 128 is capable of a limited endwise motion through its bearings in the hangers 75 and 76. A spring 145 (Fig. 18) is located upon the shaft 128 adjacent the hanger 75, and one end of the spring bears upon the hanger 75. The other end of the spring bears upon a collar 146 which is affixed to the shaft 128 and the spring 145 therefore acts 55 to urge the shaft 128 in a righthand direction as the machine is viewed in Fig. 18. The endwise movement of shaft 128 under the influence of spring 145 is limited by a stop nut 147 (Fig. 28) which is threaded upon a collar 149 affixed to the shaft 128 inside of the hanger 76. By rotating the nut 147 upon the collar 149, the endwise movement of shaft 128 may be adjusted, and this may be fixed by tightening the nut 148 which serves as a lock nut.

To impart a leftwise movement to the shaft 128, it is acted upon by a lever 151 which is pivoted at 152 to a lug 153 projecting from the hanger 76. The upper end of lever 151 carries a bolt 154 which is axially in line with shaft 128. This bolt 154 may be turned in order to 60 vary its position within the upper end of lever 151 and thereby vary the extent of the axial movement which will be imparted to the shaft 128 in a leftwise direction. The lower end of lever 151 is adapted to be engaged by a button 75

155 (Fig. 29) affixed to the side of the cam 81. To the lower end of the lever 151 may be affixed a shoe 156 to receive the thrust of the button 155 during the rotation of the cam 81. A spring 150 urges shoe 156 away from the face of cam 81.

The endwise movement of shaft 128 under the action of the button 155 will cause the side arms 122, 123, to also move in a direction parallel with the needle row. Because the welt bar 65 is held in fixed position between the arms 122, 123 by means of the flanges 120, 121 of the pins 118, 119, respectively, which bear upon the inner faces of the upper portions of the arms 122, 123, when the arms 122, 123 are moved with the endwise movement of the shaft 128, the welt bar 65 will be moved correspondingly.

The pins 118 and 119 by bearing upon the side arms 122 and 123 serve to hold upwardly the welt bar 65 when the welt bar 65 is in a rearward position toward the needles. In order to hold the welt bar 65 upwardly when it is in a position spaced forwardly from the needles, as in Fig. 17, the arms 67 and 68 are provided with pins 164 and 165, respectively, which ride on rail plates 160, 161. The pin 165 is carried by a bracket 166 (Fig. 19) which is affixed to a lug 167 projecting from the outer side of the arm 68. The pin 164 is supported in a like manner from the arm 67 by bracket 157 and lug 158 (Figs. 30 and 32).

The rail plates 160, 161 are affixed to the outer sides of rail bars 162, 163, respectively. The rail bars 162, 163 are affixed to the top of the trough member 77 and their rearward ends extend close to the needle row and their forward ends extend close to the fabric take-up means at the front of the machine. The upper surfaces of the rail bars 162, 163 serve to support the welt rod which is ordinarily employed in connection with the turning of the welt of a full fashioned hose. The upright portions of these side rails may be offset in a direction away from each other above the rail bars 162, 163, by means of a rib along their lower edges as appears at 159 in Fig. 30.

As has been noted, when the welt bar 65 is at a distance away from the needles, it and the arms 67 and 68 are supported by the pins 164 and 165 which ride on the guide plates 160 and 161, respectively. When the welt bar is toward the needles, the pins 118 and 119 ride upon the upper surfaces of the arm portions 124 and 125, respectively, to support the welt bar. This arrangement is of importance because it leaves a gap 144 (Fig. 17) between the forward ends of the arm portions 124, 125, and the rearward portions of the guide plates 160, 161 through which the operator may pass the yarns which are handled by the machine. By passing these yarns through these gaps, they may be attached in the usual manner to clamping means (not shown) which are ordinarily attached to the trough member 77. It will be understood, however, that if desired, the arm extensions 124, 125 could extend forwardly sufficiently far toward the fabric take-up means so that the guide plates 160, 161 could be eliminated, but this latter arrangement would lack the convenience of the structure which is illustrated.

The welt rod 170 initially occupies a position upon the top of the welt bar 65 (Figs. 33, 34). It rests against stop pins 173 projecting from uprights 174 secured to the rear of the welt bar 65, as shown in detail in Fig. 34.

Slightly inwardly from the ends of the welt rod 170 are affixed plates 176. The distance 76

between the plates 176 is slightly greater than the length of welt bar 65 so that the plates 176 will not grip the ends of the welt bar. To the lower ends of the plates 176 are affixed pins 177 having therein near their ends grooves 178. These grooves 178 will receive the hooks 179 of the belts 180, which are attached to the reel 181 of the take-up mechanism.

At the start of a new fabric, the welt rod 170 will be in its position upon the top of welt bar 65, and the hooks 179 will be attached to the pins 177. To resist the pull of the take-up belts, lugs 182 are provided upon a lower extension of the side arms 67 and 68, and the lower ends of the plates 176 bear against them (Fig. 35). The pull of the take-up belts tends to turn the plates 176 about the lugs 182 as a fulcrum, and move the rod 170 away from stop pins 173 (Fig. 34), inasmuch as the pull is applied to the pins 177 which are below the lugs 182.

A pusher bar 183 serves to resist this tendency of the take-up belts to dislodge the welt rod 170 from its position on the top of the welt bar 65, and also serves to dislodge the welt rod 170 at the desired time. For the pusher bar 183 to act to retain the welt rod upon the top of the welt bar, its end is formed with a hook 190 (Fig. 33) to positively engage the welt rod 170.

This pusher element 183 is pivotally connected to the upper arm of a bell crank lever 184 which is pivotable about the pin 164 by which it is supported (Figs. 30 and 32). A roller 185 is pivotally connected to the other arm of the bell crank lever 184, and this roller 185 will be acted upon by an upward movement of T-shaped trip member 186. When the trip member 186 is urged upwardly so as to strike the roller 185, the pusher bar 183 is caused to move toward the rod 170 and dislodge it from the top of the welt bar 65. The rod 170 then falls downwardly until the projecting ends 175 of rod 170 strike the upper surface of the guide rails 162, 163. These ends 175 move along upon this upper surface during the subsequent knitting of the fabric, under the pull of the take-up belts 180 as shown in Fig. 36.

When the welt rod 170 is dislodged, it moves downwardly past the face of the welt bar 65 and points 50 and upon the fabric. To prevent the welt rod from striking the points 50 during this downward movement, guards 189 are carried by the welt bar 65 at the ends of the point row. These guards 189 are held in the welt bar in the same manner that the points themselves are held, and are about as thin as the points. However, the guards are wider and slightly longer than the points, as shown in Figs. 33 and 34, so that the welt rod will ride upon the guards and cannot strike the points. If the points 50 were to strike the welt rod 170, nicks might be made in the rod which would catch in the fabric.

The pusher bar 183 is urged to a retracted position by means of a spring 187 which extends from it to a pin on the side of arm 67. A pin 188 (Fig. 30) carried by bracket 157 serves as a stop to limit the rearward movement of the pusher bar 183 under the influence of the spring 187. Also, the spring 187 exerts a downward pull upon the pusher bar 183, so that its hooked end will bear more firmly upon the welt rod 170, as shown in Fig. 33.

To prevent the welt rod 170 from falling down upon the fabric in the event that it is inadvertently prematurely dislodged, guards 168 are attached at the ends of the picot rod 169 by screws which pass through holes 171 in the

guards (Figs. 42, 43, 44). These holes 171 are elongated to permit adjustment of the guards to bring their forwardly projecting portions 172 in line with the projecting ends 175 of the welt rod 170. These forward extensions 172 should be so long that they will prevent the welt rod from dropping upon the fabric until sufficient fabric has been knit so that the welt rod cannot strike the knitting needles 55. The picot rod is disclosed in Patent No. 1,986,577 to Kenneth Howie, dated January 1, 1935.

The T-shaped trip member 186 is capable of up and down movement. To permit this, the stem portion 191 of the T-shaped trip member is located in a groove 192 in the side of the guide bar 162. The guide plate 160 retains the stem 191 in this groove 192. To provide additional guiding support for the stem 191, a guide block 193 may be secured to the lower side of the guide rail 162. This guide block 193 may also have formed in it a groove 194 (Fig. 31) in line with the groove 192 to receive the stem 191.

To move the T-shaped trip member 186 upwardly, a cam element 196 is fixed by screw 197 to the outer side of cam 138. This cam element 196 provides a peripheral surface 198 concentric with the axis of shaft 88 through an arc of approximately an eighth of a turn, for a reason to be explained.

The cam element 196 also acts to initiate the operation of auxiliary fabric take-up means to place increased tension upon the fabric after the welt rod 170 is directly drawing upon the fabric. This increased take-up tension is desirable to compensate for the frictional slippage of the fabric around the rod as the latter part of the welt is knit, and is desirable to maintain the same tension in the fabric which was present before the welt rod dropped upon the fabric. In this latter respect, it will be noted that before the welt rod 170 is dropped upon the fabric, the tension of the take-up is applied to the single length of fabric being knit, whereas after the welt rod is folded in the fabric, the take-up tension is divided between the two folds of fabric. If the take-up tension were not increased after the welt rod is folded in the fabric, a noticeable difference in the stitch length might occur.

It is desirable that this increased tension be applied immediately upon the dislodging of the welt rod, and for this reason, a ratchet wheel 207 is affixed rigidly to the take-up reel 181. The usual take-up includes the ratchet wheel 208 which drives the reel 181 through a torsion spring 209 (Fig. 41). Rotation of the ratchet wheel 207, therefore, immediately tensions the fabric, since it does not act through a torsion spring.

To rotate the ratchet wheel 207, a supplemental driving mechanism is employed which is a substantial duplicate of the usual mechanism for driving ratchet wheel 208. This supplemental driving mechanism includes a pawl 210, the forward end of which has a blade 211 to bear upon ratchet wheel 207, and the rearward end of which is pivoted to a lever 212. This lever 212 is pivoted upon a pin 213 which is carried by the side frame 78. The pivot pin 213 occupies the same position of the pivot pin for the usual take-up driving mechanism, but is longer in order to accommodate the parts of the supplemental driving mechanism.

The lower end of lever 212 is acted upon by a cross pin 214 carried by the reciprocating

drive rod 215. The drive rod 215 and cross pin 214 are the same as in the usual construction, except that the present cross pin 214 is longer to reach to and bear upon the lever 212. The drive rod 215 is supported in a bearing 216 on the side frame 78.

To the lower end of lever 212 is connected one end of a spring 221. The other end of the spring is connected to an adjusting bolt 222 by which the tension in the spring may be varied. The adjusting bolt passes through a hole in rib 220 beneath the end of trough 11. It is the force exerted by this spring 221 which serves to drive ratchet wheel 207 and thereby take up the fabric, and a consequent adjustment of the tension in the spring alters the tension upon the fabric.

Also pivoted upon the pivot pin 213 is a retaining dog 217 having a tooth 218 which will bear upon the ratchet wheel 207 and prevents its reversed rotation. A coil spring 219 encircling the pivot pin 213 and extending between lever 212 and dog 217 serves to urge the dog toward ratchet wheel 207.

A shield 223 is also pivoted upon pivot pin 213. A forward extension 224 of this shield lies close to the ratchet wheel 207, and the blade 211 of the pawl 210 is wide enough to bear upon this forward extension 224. When the forward extension 224 is elevated, it lifts the blade out of contact with the ratchet wheel 207, so that no drive is effected, although the pawl is constantly reciprocating.

The shield 223 is turned about the pivot pin 213 by a bracket 226 which bears upon the rearward extension 225 of the shield. This bracket 226 is affixed to the stem 191 of the T-shaped trip member 186. A spring 227 serves to urge the stem 191 downwardly and thereby normally hold the forward extension of the shield 223 in elevated position. One end of this spring 227 is affixed to the rail plate 160 and the other end bears downwardly on the bracket 226.

When the cam element 196 acts to lift the stem 191, the bracket 226 is lifted and allows the forward extension 224 of the shield 223 to lower and permit the blade 211 to engage the ratchet wheel 207. Due to the length of the cam element 196, this active operation of the pawl 210 continues throughout the knitting of the welt after the welt rod drops upon the fabric.

When the cam element 196 passes from beneath the stem 191, the bracket 226 swings the shield 223 to lift the pawl 210 from the wheel 207. This also removes the dog 217 from the ratchet wheel 207 by reason of a pin 228 projecting from the dog into an opening in the shield. Such a release of the pawl 210 and dog 217 immediately frees the take-up reel 181 from the supplemental take-up mechanism, so that only the usual take-up mechanism is active.

In order to manually release the supplemental take-up mechanism, the pawl 210 is provided with a handle 229 by which the blade 211 can be lifted. This also lifts the dog 217, as a pin 230 carried by the dog 217 projects over the pawl 210.

Attached to the uprights 174 are stop bolts 200 which will bear against the forwardmost narrowing bar 201 of the narrowing frame 203 when the parts are in the position of Fig. 24. Attached to the fixed bar 202 of the narrowing frame 203, by means of brackets 204, are hooks 205 (Fig. 17). These hooks will receive the pins 118 and 119 when the parts are in the position of Fig. 24. Because of the stops 200 and hooks 205, the welt points 50 will be accurately positioned with re-

spect to the needles and transfer of the loops from the points to the needles will be assured. Since the narrowing frame will control the motion of the welt points at this time, it is not necessary for cam 138 to exert any control and for this reason there should be no contact between cam 138 and the shoe follower 142, as shown in Fig. 24, at this time.

In the operation of the machine, the parts initially occupy the position shown in Figs. 17, 18, 19, and 23. At this time, the roller 86 is at the position marked 0 on cam 87 in Fig. 38, and the nose 142 is at the position marked 0' on cam 138. Also at this time a high button 111 on pattern drum A is beneath lever 109, and has moved shield 104 inwardly so that the pawl 95 may engage notch 92b. Rotation of the main cam shaft will therefore cause, through the action of the pawl 95, rotation of the cam shaft 88.

From the position shown in Figs. 17, 18, 19, and 23, the main cam shaft will make one complete rotation, and this will cause the auxiliary cam shaft 88 to make a quarter turn. Such a quarter turn movement of cam shaft 88 will bring the point marked x on cam 87 to the roller 86, so that the points 50 will have been moved part way toward the needles. The point marked x' on cam 138 will have been brought to the shoe 142, and this will cause a slight lifting movement of the side arms 122, 123. During this first complete rotation of the main cam shaft, the needles will have passed through a knitting stroke, but no knitting will have been performed because no yarn will have been laid during this time.

The auxiliary cam shaft 88 will be rotated by the next rotation of the main cam shaft, due to a low-button 110 being under lever 109. The pawl 95 will engage notch 92c at this time to drive the auxiliary cam shaft.

During the first portion of this next full rotation of the main cam shaft, a yarn will be laid down against the needles, and the sinkers will have advanced to the rear of the movement of the yarn carrier guide to sink the yarn. At the end of this time, the auxiliary shaft 88 will have been moved so that the point 1 on the periphery thereof will be brought to the roller 86, thus moving the points 50 closer to the needles. The point 1' on cam 138 will now bear on the nose 142.

In continuing the rotation of the main cam shaft in this second full rotation, the dividers will be moved outwardly. At the end of this time, the needles will move to the press bar 58. Also, the auxiliary cam shaft 88 will have turned so that the point 2 on cam 87 will bear on roller 86 and will have caused the points 50 to be brought to the beard side of the needles, as shown in Fig. 2. This rotation of the auxiliary cam shaft 88 will also have brought the point 2' on the periphery of cam 138 to the nose 142, but inasmuch as the portion of the periphery between points 1' and 2' is approximately arcuate, the side arms 122 and 123 will remain at the same height.

Only a portion of the second quarter turn of auxiliary cam shaft 88 under the influence of pawl 95 will have been accomplished by this time.

During the rotation of the main cam shaft in continuing its second full rotation, the needles will be brought to the yarn drop off position shown in Fig. 3, and the auxiliary cam shaft 88 will have been moved a slight arcuate distance so that the point 3 on the cam 87 is opposite roller 86. Since the point 3 is further inwardly than the point 2 on cam 87, the points 50 will have been moved forwardly toward the needles, as

shown in Fig. 3. At this same time, the point marked 3' on the cam 138 will be at the nose 142, and this will have caused the points 50 to have dropped to the position shown in Fig. 3.

Further movement of the main cam shaft in continuing through its second full rotation will move the needle to the position shown in Fig. 4, in which the yarn is brought below the tops of the knockover bits 59. This movement of the main cam shaft will have moved the auxiliary cam shaft 88 so that the point 4 on the periphery of cam 87 is at the roller 86 to thereby position the point 50 as shown in Fig. 4. Also the point 4' on cam 138 will be opposite the nose 142 so that the point 50 will be at the level shown in Fig. 4. At this time, the shoe 156 of the shogging lever 151 will be upon the button 155 on the side of cam 87, and this will cause the points 50 to be shogged approximately a half needle space lengthwise of the needle row. The needles will now move toward the press bar 58 and this will bring the yarn against the points 50, so that the yarn will be caught upon the shoulders 51. Then the button 155 will be removed from the shogging lever 151, and the points 50 will move back into line with the needles.

During the completion of the second full rotation of the main cam shaft, the needle will be advanced upwardly to receive a new yarn, and the auxiliary cam shaft 88 will have completed its second quarter turn movement. By this time, the low button 110 will have been moved away from lever 109, so that the auxiliary cam shaft 88 will remain idle during further rotations of the main cam shaft. Also, by this time cam shaft 88 will have completed its second quarter turn and brought the point 5 of the cam 87 opposite the roller 86, so that the welt bar may move away from the needles as the welt fabric is knit. The roller 86 will not immediately move into contact with the cam in position 5, however, since the yarn will be caught on the points, and this will hold the arms 69 and 70 toward the needles. The point marked 5' on the cam 138 will be opposite the nose 142 to thereby determine the level of the points 50.

Subsequent rotations of the main cam shaft after this second full rotation will cause ordinary knitting to be performed, so that a length of fabric as shown in Fig. 5 will be knit. During this regular knitting of the welt portion of the fabric, the auxiliary cam shaft 88 will remain in fixed position, so that the roller 86 will be opposite the point 5 on cam 87, and the nose 142 will be at the point 5' on cam 138. The auxiliary cam shaft 88 will remain in this fixed position, because no button of pattern drum A will be under lever 109, although the pawl 95 will oscillate repeatedly under the influence of its actuating cam 100 on the main cam shaft.

It will be understood that when the roller 86 passes beyond the nose of cam 87 between the points 4 and 5 thereon, the roller will not immediately drop into contact with the cam at point 5, inasmuch as the fabric will serve to hold the roller 86 outwardly away from the point 5. However, as the welt fabric is knit and the points 50 move away from the needles under the influence of the take-up bands 180, the roller 86 will gradually move inwardly toward the point 5 on cam 87.

After a portion of the welt fabric has been knit, as shown in Fig. 5, a low button 110 will be brought under the end of lever 109 so that shield 104 will be moved inwardly and permit the pawl 95 to engage notch 92d. The pawl will not

engage in notch 92e at this time, because a high button 111 must be under lever 109 to permit such an engagement. As notch 92d will be the only one which can be engaged, only an eighth of a turn will be imparted to the auxiliary cam shaft 88.

This eighth of a turn of shaft 88 will first act to dislodge the welt rod 170, and will then move the points 50 slightly toward the needles and also elevate the points, so that the relation of Fig. 6 10 results. The welt rod 170 is now folded in the fabric, and tension of the take-up belts will be applied directly to the fabric.

The welt rod 170 is dislodged by the action of cam element 196 against stem 191, and since the 15 bracket 226 is attached to this stem, the shield 223 is moved to inoperative position so that the pawl 210 engages the ratchet wheel 207. The increased tension afforded by pawl 210 and ratchet 207 is rapidly applied to the fabric, and is maintained throughout the subsequent knitting of the 20 welt.

For the position of Fig. 6, the roller 86 will be at point 6 on cam 87, and the nose 142 will be at point 6' on cam 138. The followers will remain at these points on cams 87 and 138 throughout the knitting of the remainder of the fabric, as appears from Fig. 6a. During this subsequent knitting the welt rod 170 moves away from the 30 needles to take up the fabric, as also appear from Fig. 6a.

After the entire welt has been knit, a high button 111 will be brought under the free end of lever 109 so that shield 104 will be moved inwardly and permit the pawl 95 to engage notch 92e 35 to rotate the auxiliary cam shaft 88. Also, at this time the main cam shaft a will be shogged so that the machine will move through its narrowing motion.

Two complete rotations of the main cam shaft are necessary to return the welt points to the needles from the position of Fig. 6a, to transfer the loops from the points to the needles, and to restore the points to their normal position shown in Figs. 17, 18, 19, and 23. The first full rotation of the main cam shaft will turn the shaft 88 an eighth turn due to notch 92e, and the second full rotation will account for a further quarter turn rotation of the auxiliary cam shaft 88 due to notch 92a. A high button 111 must come into action to cause engagement with notch 92e, and a low button 110 causes engagement with notch 92a.

During the first part of this movement, the cam element 196 will be removed from stem 191, so that shield 223 will act to lift pawl 210 from ratchet wheel 207. The additional tension afforded by ratchet wheel 207 will thereby be released and only the tension afforded by the usual ratchet wheel 208 will be applied to the fabric.

The first full rotation of the main cam shaft to return the loops to the needles will be a regular knitting cycle and will bring the needles to the position of Fig. 6b. In this position, the needles are just coming up from finishing the knitting course, and it is at this point that the main cam shaft shogs over to the narrowing position. As has been noted, this first rotation of the main cam shaft will rotate the auxiliary cam shaft an eighth turn to bring the welt points toward the needles, as shown in Fig. 6b.

The second full rotation of the main cam shaft to return the loops to the needles will move the needles through a narrowing cycle and no yarn will be laid down. Between the positions shown

5 in Fig. 6b and Fig. 7, the main cam shaft will have moved through a portion of this second full rotation and the needles will have gone down and up again to complete the first half of the narrowing operation, or that half of the narrowing operation in which the stitches are normally taken from the needles. During this time, the auxiliary cam shaft will make a partial movement in its last quarter turn and will move the points from Fig. 6b to Fig. 7. This will bring point 1 of cam 87 and point 1' of cam 138 to their respective followers, to elevate the points as in Fig. 7, so that they will pass over the tops of the needles.

At this same time, the narrowing frame has been lowered so that the hooks 205 are in line with the movement of the points 50 toward the needles. As a consequence, the pins 118 and 119 enter the hooks as shown in Figs. 24 and 25, and thereafter the narrowing frame will determine the up and down movement of the welt bar until the welt bar is withdrawn under the action of the spring 89 as permitted by the cam 87 so as to remove the pins 118 and 119 from the hooks 205. Since the narrowing frame will control the welt bar in this manner, the depression at 8', 9', 10', and 11' in cam 138 is deepened so as to be out of contact with the nose 142, as shown in Fig. 24. However, hooks 205 may be eliminated and the cam 138 be so contoured in this region that it will impart to the points their necessary up and down movements.

From the position of Fig. 7 on, the machine goes through the second half of its narrowing cycle, and the loops upon the welt points are transferred to the needles. The first movement of the main cam shaft beyond Fig. 7 will cause the needles to drop as shown in Fig. 8, and will rotate the auxiliary cam shaft 88 so that point 8 of cam 87 will determine the forward position of the points. As has been noted, hooks 205 are now exerting control over the points to move them downwardly.

Continued operation of the machine will bring the needles to the position of Fig. 9, and points 50 will occupy the relative position shown due to points 9 and 9' on cams 87 and 138, respectively. Further rotation of the main cam shaft will position the needles as in Fig. 10, and will turn the auxiliary cam shaft so that roller 86 will be upon point 10 of cam 87 and nose 142 will be opposite point 10' of cam 138.

Still further rotation of the main cam shaft will elevate the needles as shown in Fig. 11, and will move cams 87 and 138 so their points 11 and 11' are opposite their followers. Point 11' is not acting, however, as hooks 205 still exert their control.

Further rotation of the main cam shaft positions the needles as in Fig. 12 and the points 50 as there shown. At the corresponding point 12 of cam 87, its contour is starting to recede to permit movement of the points 50 away from the needles. Also point 12' of cam 138 is at a high point to maintain the points 50 at a level above the tops of the needles.

65 At the end of the second full turn of the main cam shaft, the auxiliary cam shaft has completed its last quarter turn so that roller 86 is at point 0 on cam 87 and nose 142 is at point 0' on cam 138. As a result the points are as shown in Figs. 17, 18, 19, and 23, where they remain throughout the subsequent knitting of the fabric.

70 During the next rotation, a yarn will be laid down and it will be knit to join the welt as shown 75 in Fig. 16. The welt is now completely closed

and the remainder of the fabric will be knit in regular manner. Due to the fact that two courses at the initial end of the fabric are joined to the fabric when the welt is knit closed, a stronger connection is established.

Although the invention has been disclosed in association with a single head full fashioned knitting machine of the type disclosed in Howie Patent No. 1,982,991, the invention is not limited to such use and may be employed in connection with multiple head full fashioned knitting machines.

We claim:

1. Welt turning apparatus for a full fashion knitting machine comprising hanger arms depending from an upper forward part of the machine framework, upright arms pivotally connected at their lower ends to the lower portion of said hanger arms, connecting arms pivotally attached to the upper ends of said upright arms and extending toward the needle row, a welt bar secured to the connecting arms and carrying a plurality of welt points, guide arms pivotally connected to the upper portion of said hanger arms and extending toward the needle row and providing upwardly facing substantially horizontal guide surfaces, said guide surfaces serving to support the welt bar, an auxiliary cam shaft rotatably mounted in said hanger arms between the pivotal connections for the upright arms and the guide arms and having cams thereon, a connection from one of the cams to said upright arms to thereby move the points to or from the needles, and another connection from another of the cams to said guide arms to thereby elevate or lower said points and cause the points to cooperate with the needles.

2. Welt turning apparatus for a full fashion knitting machine comprising hanger arms depending from an upper forward part of the machine framework, upright arms pivotally connected at their lower ends to the lower portion of said hanger arms, connecting arms pivotally attached to the upper ends of said upright arms and extending toward the needle row, a welt bar secured to the connecting arms and carrying a plurality of welt points, guide arms pivotally connected to the upper portion of said hanger arms and extending toward the needle row and providing upwardly facing substantially horizontal guide surfaces and overlying downwardly facing guide surfaces, said connecting arms having pins to ride along said upwardly facing guide surfaces and enter under said overlying downwardly facing guide surfaces, an auxiliary cam shaft rotatably mounted in said hanger arms between the pivotal connections for the upright arms and the guide arms and having cams thereon, a connection from one of the cams to said upright arms to thereby move the points to or from the needles, and another connection from another of the cams to said guide arms to thereby elevate or lower said points and cause the points to cooperate with the needles.

3. Welt turning apparatus for a full fashion knitting machine comprising hanger arms depending from an upper forward part of the machine framework, upright arms pivotally connected at their lower ends to the lower portion of said hanger arms, connecting arms pivotally attached to the upper ends of said upright arms and extending toward the needle row, a welt bar secured to the connecting arms and carrying a plurality of welt points, a shaft mounted for rotatable and endwise movement in the upper portion

of said hanger arms, guide arms secured to said shaft and extending toward the needle row and providing upwardly facing substantially horizontal guide surfaces, said guide surfaces serving to support the welt bar and also fix its endwise position, an auxiliary cam shaft rotatably mounted in said hanger arms between the pivotal connections for the upright arms and the guide arms and having cams thereon, a connection from one of the cams to said upright arms to thereby move the points to or from the needles, other connections from another of the cams to said guide arms to thereby elevate or lower said points and cause the points to cooperate with the needles, and another connection from one of said cams to move said shaft endwise and thereby cause the points to move a part needle space to enable their free passage between the needles.

4. Welt turning apparatus for a full fashion knitting machine having a narrowing frame, comprising a welt bar carrying a plurality of welt points, mechanical means operated by the knitting machine to urge the welt bar toward or away from the needles, guide arms for supporting the welt bar in its movement toward or away from the needles, a pivotal mounting for said guide arms permitting their up or down movement, and other mechanical means operated by the knitting machine to turn the guide arms about said pivotal mounting and determine the up or down position of said guide arms, and means carried by the narrowing frame to engage with and move the welt bar with the narrowing frame through at least a portion of the movement of the points when cooperating with the needles.

5. Welt turning apparatus for a full fashion knitting machine having a narrowing frame, comprising a welt bar carrying a plurality of welt points, mechanical means operated by the knitting machine to urge the welt bar toward or away from the needles, guide arms for supporting the welt bar in its movement toward or away from the needles, a pivotal mounting for said guide arms permitting their up or down movement, and other mechanical means operated by the knitting machine to turn the guide arms about said pivotal mounting and determine the up or down position of said guide arms, and means carried by the narrowing frame to engage with and move the welt bar with the narrowing frame through the regular delivery movement of the narrowing frame to cause the welt points to cooperate with the needles.

6. Welt turning apparatus for a full fashion knitting machine comprising a welt bar carrying a plurality of welt points, said points having a yarn retaining shoulder on their sides facing the needles when the points are on the operating side of the needles, means for moving the points to a position on the operating side of the needles and with their shoulders below the yarn on the needles, means for causing relative movement between the points and the needles to bring the points to the opposite side of the needles and thereby catch the yarn upon the shoulders, means for placing a welt rod upon the knit welt fabric, means for moving the points toward the needles to fold the welt rod in the fabric and cause the points to pierce through the fabric, and means for moving the points with the needles to transfer the loops from the points to the needles.

7. Welt turning apparatus for a full fashion knitting machine comprising a welt bar carrying a plurality of welt points, said points having a yarn retaining shoulder on their sides facing the

needles when the points are on the operating side of the needles, means for moving the points to a position on the operating side of the needles and with their shoulders below the yarn on the needles, means for causing relative movement between the points and the needles to bring the points to the opposite side of the needles and thereby catch the yarn upon the shoulders, means acting after a portion only of the welt fabric has been knit for folding a welt rod into the fabric and therewith cause the points to pierce through the fabric, and means acting after the complete welt fabric has been knit for moving the points with the needles to transfer the loops from the points to the needles.

8. Welt turning apparatus for a full fashion knitting machine comprising a welt bar carrying a plurality of welt points for engaging an initial course of the welt fabric, means including a welt rod for tensioning the welt fabric away from the needles as the welt fabric is being knit, means for moving the points to the needles after the welt rod is in place and thereby causing said points to pierce through the fabric upon said movement of the points toward the needles, means retaining said initial course of fabric upon the points during said movement of the points, and means for moving the points with the needles to transfer the loops from the points to the needles.

9. Welt turning apparatus for a full fashion knitting machine comprising a welt bar carrying a plurality of welt points, said points having a yarn retaining shoulder on their sides facing the needles when the points are on the operating side of the needles, means for positioning the points on the operating side of and in line with the needles, means for moving the points out of alignment with the needles, means causing relative movement between the points and the needles to bring the points on the opposite side of the needles and thereby cause the yarn to be caught upon the points above said shoulders thereof, and means restoring the points into alignment with the needles for subsequent knitting of the fabric.

10. Welt turning apparatus for a full fashion knitting machine comprising a welt bar carrying a plurality of welt points, said points having a yarn retaining shoulder on their sides facing the needles when the points are on the operating side of the needles, means including a welt rod for tensioning the welt fabric away from the needles as the welt fabric is being knit, means for moving the points to the needles after the welt rod is in place, said points having reduced ends to pierce through the fabric upon said movement of the points toward the needles, and means for moving the points with the needles to transfer the loops from the points to the needles.

11. The method of turning the welt of a fabric being knit upon a full fashion knitting machine which comprises holding loops of an initial course of the fabric upon points as the fabric is being knit, bringing the fabric against the ends of the points while retaining the first course of the fabric upon the points, and piercing the points through the fabric to thereby cause a second course of the fabric to be upon the points, and then transferring to the needles from the points both courses of fabric which are upon the points.

12. The method of turning the welt of a fabric being knit upon a full fashion knitting machine which comprises holding loops of an initial course of the fabric upon points having a yarn retaining shoulder on their sides which face away from the needles as the fabric is being knit, bringing

the fabric against the ends of the points, and piercing the points through the fabric to thereby cause a second course of the fabric to be upon the points, and then transferring to the needles from the points both courses of fabric which are upon the points.

13. The method of turning the welt of a fabric being knit upon a full fashion knitting machine which comprises holding loops of an initial course of the fabric upon points as the fabric is being knit, piercing the ends of the points through the fabric immediately adjacent to said initial course while retaining the first course of the fabric upon the points to thereby place a second course of the fabric upon the points, and then transferring to the needles from the points both courses of fabric which are upon the points.

14. The method of turning the welt of a fabric being knit upon a full fashion knitting machine which comprises holding loops of an initial course of the fabric upon points as the fabric is being knit, moving the points toward the needles after welt fabric is knit to thereby cause the points to pierce through a second course of the fabric, and then transferring to the needles from the points both courses of fabric which are upon the points.

15. The method of turning the welt of a fabric being knit upon a full fashion knitting machine which comprises holding loops of an initial course of the fabric upon points as the fabric is being knit, moving the points toward the needles after welt fabric is knit while the fabric is urged away from the needles to thereby cause the points to pierce through a second course of the fabric, and then transferring to the needles from the points both courses of fabric which are upon the points.

16. The method of turning the welt of a fabric being knit on a full fashion knitting machine which comprises locating on the operating side of the needles a plurality of welt points each having a yarn retaining shoulder on its side facing the needles when the points are on the operating side of the needles, said points being positioned with their shoulders below the yarn on the needles, moving the points through the needle row to the opposite side of the needles to thereby catch the yarn upon the shoulders, placing a welt rod upon the welt fabric and tensioning it away from the needles, moving the points toward the needles to thereby pierce the ends of the points through the fabric upon said returned movement of the points to the needles, and thereafter transferring the loops from the points to the needles.

17. The method of turning the welt of a fabric being knit on a full fashion knitting machine which comprises locating on the operating side of the needles a plurality of welt points each having a yarn retaining shoulder on its side facing the needles when the points are on the operating side of the needles, said points being positioned with their shoulders below the yarn on the needles, moving the points through the needle row to the opposite side of the needles to thereby catch the yarn upon the shoulders, knitting a loose course adjacent to the loops caught upon the points, placing a welt rod upon the welt fabric and tensioning it away from the needles, moving the points toward the needles to thereby pierce the ends of the points through said loose course of the fabric upon said movement of the points toward the needles, and after the welt fabric has been knit transferring the loops from the points to the needles.

18. Welt turning apparatus for a full fashion

knitting machine having fabric take-up mechanism, comprising a welt rod, the take-up mechanism being continuously connected to the welt rod throughout the knitting of the fabric, a seat upon which the welt rod is retained in position above the fabric as the welt fabric is first being knit, and a pusher operated by the machine after knitting of the welt for dislodging the welt rod from said retaining seat to permit the welt rod to fall upon the fabric.

19. Welt turning apparatus for a full fashion knitting machine having fabric take-up mechanism, comprising a welt rod, side plates connected to the ends of the welt rod, the take-up mechanism being continuously connected to the end plates of the welt rod throughout the knitting of the fabric, means retaining the welt rod in position above the fabric as the welt fabric is being knit, said retaining means including a fulcrum against which the side plates bear at a point between the welt rod and the point of attachment to the side plates of the take-up, and means operated by the machine after at least a portion of the welt is knit to bear upon the welt bar and tilt it about said fulcrum for dislodging the welt rod from said retaining means and thereby permit the welt rod to fall upon the fabric.

20. Welt turning apparatus for a full fashion knitting machine having fabric take-up mechanism, comprising a welt bar carrying a plurality of welt points for engaging an initial course of the fabric, means supporting the welt bar above the level of the fabric and for movement away from the needles, a welt rod, means connecting the take-up mechanism to the welt rod throughout the knitting of the fabric, said welt bar having a seat thereon retaining the welt rod above the fabric as the welt fabric is being knit, and means operated by the machine after at least a portion of the welt is knit for dislodging the welt rod from its seat on the welt bar to permit the welt rod to fall upon the fabric.

21. Welt turning apparatus for a full fashion knitting machine having fabric take-up mechanism, comprising a welt bar carrying a plurality of welt points for engaging an initial course of the fabric, means supporting the welt bar above the level of the fabric and for movement away from the needles, a welt rod, means connecting the take-up mechanism to the welt rod throughout the knitting of the fabric, said welt bar having a seat thereon retaining the welt rod above the fabric as the welt fabric is first being knit, and means operated by the machine after at least a portion of the welt is knit for dislodging the welt rod from its seat on the welt bar to permit the welt rod to fall upon the fabric, said dislodging means including a trip element extending lengthwise of the path of movement of the welt bar and a linkage carried by the welt bar and presenting one portion to be contacted by the trip element and another portion to act upon the welt rod.

22. Welt turning apparatus for a full fashion knitting machine having fabric take-up mechanism, comprising a welt bar carrying a plurality of welt points for engaging an initial course of the fabric, means connected to the welt bar for urging it toward or away from the needles, a welt rod seated upon the welt bar but dislodgable therefrom, said take-up being connected to the welt rod, guide elements for the welt bar to raise or lower the points in their movement toward or from the needles, a cam shaft having cams thereon, connections from one of said cams

to move the welt bar toward or from the needles, connections from another of said cams to elevate or lower said guide arms, and other connections from one of said cams to dislodge the welt rod from the welt bar so that it will fall upon the welt fabric.

23. A welt implement having a shoulder for engaging a loop and a terminal extension below said shoulder for penetrating the fabric below the loop on the shoulder said terminal extension being laterally thinned relative to the portion of the implement above said shoulder.

24. A welt point for a full fashion knitting machine comprising a stem portion having a curved portion at its end for engaging the thread, and a yarn retaining shoulder in the concaved side of the curved portion.

25. A welt point for a full fashion knitting machine comprising a step portion having a curved portion at its end for engaging the thread, and a yarn retaining shoulder in the concaved side of the curved portion, the end of the stem being thinned laterally with respect to the concave side.

26. A welt point for a full fashioned knitting machine comprising a stem portion having a yarn retaining shoulder thereon adjacent the free end of the stem, the portion of the point providing said shoulder being of less width than the portion of the stem immediately therebehind whereby said portion of the stem has a yarn shielding effect with respect to the shoulder.

27. A welt point for a full fashion knitting machine comprising a stem portion having a curved portion at its end for engaging the thread, and a yarn retaining shoulder in the concaved side of the curved portion, there being an eye in the stem above said yarn retaining shoulder.

28. A welt point for a full fashion knitting machine comprising a stem portion having a curved portion at its end for engaging the thread, said concaved side having a notch therein spaced from the end of the stem.

29. A full fashion knitting machine comprising a welt turning implement having a shoulder for holding a loop and a terminal extension beyond said shoulder for penetrating the fabric connected with said loop, and means for operating the welt implement and controlling the fabric to cause the extension of the implement to penetrate the fabric adjacent the loop on said shoulder, substantially as described.

30. In welt turning mechanism, the combination of welt points having each a shoulder on the side that faces the operating side of the needle when the said point is on the operating side of the needle, a welt rod over which the welt is turned, said welt point having a terminal portion below the shoulder for piercing the fabric after the same is turned over the welt rod.

31. Welt turning mechanism for a full fashion knitting machine comprising a series of points each having a shoulder to engage and hold a loop of the initial row, means for operating said points in respect to the needles for turning the welt while maintaining said points in substantially upright position depending from their carrying bar, said points having each an extension below its shoulder and means for presenting the fabric to the said extension to be penetrated thereby while the initial loops remain on said shoulders.

32. Welt turning apparatus for a full fashion knitting machine comprising a welt bar, a plurality of welt points carried by said bar, supporting means mounting said welt bar for move-

ment toward and away from the needles, a welt rod seated upon the welt bar during at least a portion of the knitting of the welt fabric, means for dislodging the welt rod to allow it to fall upon the fabric, and guards carried by said welt bar and of greater size than said points to prevent the welt rod from contacting said points in its fall.

33. In a full fashion knitting machine having knitting needles, a welt turning apparatus comprising a welt bar, a plurality of welt points carried by said bar, supporting means mounting said welt bar for movement toward and away from the needles, a welt rod, means for supporting the welt rod above the welt fabric as it is initially being knit, means for dislodging the welt rod to cause it to fall upon the fabric, and guard arms carried by the machine above the needles and extending from the needles in the direction of movement of the fabric to prevent fall of the welt rod between the needles and points in the event of a premature dislodgment of the welt rod.

34. In a full fashion knitting machine having knitting needles and a picot bar, a welt turning apparatus comprising a welt bar, a plurality of welt points carried by said bar, supporting means mounting said welt bar for movement toward and away from the needles, a welt rod, means for supporting the welt rod upon the welt bar and above the welt fabric as it is initially being knit, means for dislodging the welt rod to cause it to fall upon the fabric, and guard arms carried by the picot bar of the machine above the needles and extending from the needles in the direction of movement of the fabric to prevent fall of the welt rod between the needles and points when the points are close to the needles.

35. A full fashion knitting machine comprising knitting needles, a fabric take-up reel, a welt bar carrying a plurality of points, means mounting the welt bar for movement toward and away from the needles, a welt rod seated upon the welt bar, take-up belts connecting the welt rod to the take-up reel, means for rotating the take-up reel as the fabric is knit to apply tension to the take-up belts, means for dislodging the welt rod from the welt bar to allow the welt rod to fall upon and become folded in the fabric, and supplemental reel rotating means for applying an increased tension in said take-up belts after the welt rod is folded in the fabric.

36. A full fashion knitting machine comprising knitting needles, a fabric take-up reel, a welt bar carrying a plurality of points, means mounting the welt bar for movement toward and away from the needles, a welt rod seated upon the welt bar, take-up belts connecting the welt rod to the take-up reel, means for rotating the take-up reel as the fabric is knit to apply tension to the take-up belts, means for dislodging the welt rod from the welt bar to allow the welt rod to fall upon and become folded in the fabric, supplemental reel rotating means for applying an increased tension on said take-up belts after the welt rod is folded in the fabric, and means for simultaneously actuating said welt rod dislodging means and said supplemental reel rotating means.

37. A welt rod comprising a rod portion, plates attached to the rod portion adjacent the ends thereof, and means for attaching a take-up to said plates.

38. A welt rod comprising a rod portion, plates attached to the rod portion adjacent the ends thereof, projections beyond said plates in line

with said rod portion, and means carried by said plates for attaching a take-up means thereto.

39. A welt rod comprising a rod portion, plates attached to the rod portion adjacent the ends thereof, and pins attached to the inner faces of said plates for connection to a take-up.

40. Welt turning apparatus for a full fashion knitting machine comprising upright arms pivotally mounted about their lower ends, connecting arms extending from the upper ends of said upright arms toward the needle row, a welt bar carrying a plurality of welt points and fixedly secured to the connecting arms with the welt points in depending relation, guide arms providing substantially horizontal guide surfaces for supporting the welt bar in its movement toward or away from the needles, means for moving the upright arms and means for moving the guide arms in timed relation to cause the welt points to cooperate with the needles.

41. Welt turning apparatus for a full fashion knitting machine having as part of the frame work a cross channel member substantially at the height of the needle bed, comprising upright arms pivotally mounted about their lower ends, connecting arms extending from the upper ends of said upright arms toward the needle row, a welt bar carrying a plurality of welt points and fixedly secured to the connecting arms with the welt points in depending relation, guide arms pivotally mounted at a point below said cross channel member, said guide arms providing substantially horizontal guide surfaces for supporting the welt bar in its movement toward or away from the needles, means for moving the upright arms and means for moving the guide arms in timed relation to cause the welt points to cooperate with the needles.

42. Welt turning apparatus for a full fashion knitting machine comprising hanger arms depending from an upper forward part of the machine frame work, upright arms pivotally connected at their lower ends to the lower portion of said hanger arms, connecting arms pivotally attached to the upper ends of said upright arms and extending toward the needle row, a welt bar carrying a plurality of welt points and fixedly secured to the connecting arms with the welt points in depending relation, guide means pivotally connected to the upper portion of said hanger arms and extending toward the needle row said guide means providing upwardly facing substantially horizontal guide surfaces which serve to support the welt bar, means for moving the upright arms and means for moving the guide means in timed relation to cause the welt points to cooperate with the needles.

43. Welt turning apparatus comprising a welt implement having a shoulder for engaging a loop and a terminal extension below said shoulder for penetrating the fabric below the loop on the shoulder, and means for returning the welt implement toward the needles after the knitting of welt fabric to cause the terminal extension to penetrate the fabric.

44. Welt turning apparatus for a full fashioned knitting machine having spaced needles comprising, a welt bar, a plurality of welt implements carried by said bar, a shoulder on each welt implement, a terminal portion on each welt implement below the associated shoulder and said terminal portion being of less thickness than a portion of the welt implement above said shoulder, means for moving the welt implements to

an operating side of the knitting needles after yarn has been laid against that side of the needles and to position said shoulders adjacent the yarn, means for moving the welt implements a half needle space lengthwise of the needle row, means for moving the welt implements and the needles relative to each other so that the terminal portions of the welt implements pass between the

5 needles and to the opposite side of the needles and thereby cause the welt implements to pick up the yarn on said shoulders and retain the yarn on the welt implements during subsequent knitting of the welt fabric.

KENNETH HOWIE.
CHARLES C. KRIEBLE.
